UNITED STATES PATENT OFFICE.

HAROLD S. LABOMBARDE, OF NASHUA, NEW HAMPSHIRE.

STACKER.

Application filed September 15, 1923. Serial No. 662,818.

To all whom it may concern:

Be it known that I, HAROLD S. LABOMBARDE, a citizen of the United States, and resident of Nashua, in the county of Hillsborough and State of New Hampshire, have invented a new and useful Stacker, of which the following is a specification.

The principal object of my invention is to improve the stacking of blanks, particularly at high speed, and especially to keep glued blanks under control to prevent popping open or separation of the glued parts.

Another object is to provide increased range so that a long as well as a short blank may be kept under control.

Other objects will be pointed out below.

A feature of my invention consists in having part of the receiving stacking means, preferably a belt, yielding to provide uniform stacking.

Another feature is means for making sure that each blank approaching the stacker will be out of the path of the next following blank.

Another feature is the wide range of adjustability of the means for delivering the blanks to the stacker.

Another feature is an adjustable positive drive forming part of the receiving mechanism.

Other features will be pointed out below.

In the drawings—

Figure 1 is an elevation of a machine embodying my invention;

Figure 2 is a plan of the same;

Figure 3 is an elevation, on a larger scale, of a portion of said machine but without any blanks;

Figure 4 is an enlarged elevation of the adjustable upper delivery mechanism;

Figure 5 is an enlarged plan of the end of the mechanism shown in Figure 4;

Figure 6 is a section on line 6—6 of Figure 4; and

Figure 7 is an end elevation, looking in the direction of the arrow in Figure 4, of a portion of the machine hereinafter described.

As my invention is applicable for use in connection with a great variety of machines for folding blanks to flat form with overlapping flaps connected by glue or other suitable material, such for example as that shown in U. S. Letters Patent No. 960,348, dated June 7, 1910, it will not be necessary

to illustrate in detail mechanism for folding or mechanism for applying glue or other adhesive and therefore I show merely the delivery end of such a folding and gluing machine, frame A, support A', driving shaft A² 60 and feed rolls A³ and A⁴ being shown in Figures 1 or 2.

Feed rolls A³ and A⁴ deliver the blanks successively in their folded and glued condition to the belts A⁵ and A⁶ which I call 65 delivery belts because they deliver to the receiving or stacking mechanism described below. Belt A⁶ is carried by pulleys A⁷ and A⁸, pulley A⁸ being driven by any suitable gearing.

Belt A⁵ runs on pulleys A⁹, A¹⁰, and A¹¹, and A¹² and cooperates with belt A⁶ to deliver the blanks successively to the receiving or stacking means, which includes belt B running on pulleys b, b' and b² and belt B' 75 running on pulleys b³, b⁴, b⁵ and b⁶. Pulley b² is fixed to shaft b⁷ to which is fixed pinion b⁸ driven by chain b⁹ which is driven by pinion b¹⁰ which has fixed connection with stud b¹¹, the latter being pivotally mounted on 80 arm b¹² which is pivotally connected to shaft b⁷. Stud b¹¹ has a suitable operative pivotal connection with arm b¹³ and fixed connection with pinion b¹⁴ driven by chain b¹⁵. Arm b¹³ is pivotally mounted on shaft b¹⁶ 85 and carries a shaft b¹⁷ to which is fixed pinion b¹⁸ driving chain b¹⁹ and to which is also fixed pinion b¹⁹ driven by gear b²⁰ fixed to shaft b¹⁶, the latter being fixed to bevel gear b²¹ meshing with bevel gear b²² fixed to 90 shaft A².

Journalled in fixed bearings is roller D which forces belt A⁵ slightly downwardly and thereby snaps down the rear end of each blank in order to make sure that there will be no interference by each blank with the next following blank.

Pivoted to the frame at e is arm E carrying pulley b⁵ and to the arm is suitably connected, as by threading, rod e' carrying weight E' which may be moved along the rod to the desired position and there held by set screw e². When blanks are not being fed through the machine the weight E' will hold pulley b⁵ up in the position shown in Figure 3 but as the blanks are fed their weight gradually forces belt B' downward and thereby forces pulley b⁵ downward against the force of weight E' so that that portion of the receiving or stacking means 100 105 110

which is below the blanks yields to accommodate the blanks so as to give perfect stack particularly at high speed.

- In using my mechanism the folded blanks, 5 each of which has had one or more flaps glued to the body portion, are delivered one after another by the cooperation of delivery belts A^5 and A^6 , each folded blank, after leaving belt A^6 , being guided downwardly 10 by that portion of the lower stretch of belt A^5 which extends in advance of or forward of, belt A^6 and by "advance" and "forward" I refer to the direction in which the folded blanks pass through the machine. 15 The forward end of belt A^5 extends forward of belt A^6 at least the length of one folded blank and just as the rear end of each blank leaves belt A^6 it is snapped or forced downwardly by roll D which engages belt A^5 at a point slightly below the line from the bottom of pulley A^9 to the top of pulley A^7 , and thus makes sure that each blank will move downwardly out of the way of the next succeeding blank and 25 this is particularly important because the broad receiving belt B' moves at a slower rate than belt A^6 and therefore each blank overlaps the next when the blanks are stacked on the belt B' .
- 30 When the first blank is fed the belt B' is in the position shown in Figure 3, the axis of pulley b^5 being substantially vertically below the axis of pulley b^2 so that pulley b^5 can not rise further, the weight E' being so 35 located as to raise pulley b^5 to this position. As the first folded blank is delivered by belts A^5 and A^6 it is received by belt B' and then between the two receiving belts B and B' . As the blanks follow one another 40 quickly they overlap and as their weight gradually increases belt B' yields downward vertically carrying with it b^5 until the latter engages the lower stretch of belt B' . The result is that stacking conditions are always 45 the same regardless of the number of blanks and there is no likelihood of any change in the angle of any incoming blank and consequently no likelihood of any blank striking belt B in such a way as to bend the edge of 50 the blank or to delay passage between the receiving belts. It will be understood that pulleys b^2 and A^9 are fixed against vertical movement and the only yielding is downwardly by belt B' , which is a slack belt, the 55 slack being taken up when the weight of the blanks forces said belt B' downward between the pulleys b^4 and b^8 .

In Figures 4 to 7 I illustrate the adjustable mounting of the upper delivery belt, frame F having bracket f forming a support for one end of shaft f^2 , held fixed to bracket f by set screw f^3 , there being a similar bracket and set screw at the other end of said shaft, which shaft carries pulley A^{11} . Bracket f^4 may be used to support

pulley A^{12} . A yoke F' has two portions f^5 and f^6 embracing shaft f^2 , portion f^6 having its ends held in gripping relation to shaft f^2 by clamp screw f^7 . Yoke F' has perforations to receive rods G and G' which may be held in the desired position by clamping member F^8 and nut F^9 . The rods G and G' may therefore be adjusted longitudinally and angularly. Rods G and G' have suitable fixed connection with member G^2 carrying pulley A^9 .

Roll D is carried by member D' through which passes bolt D^2 , the latter passing also through the arms of yoke D^3 , these arms being split for engagement with rods G and G' so that when nut D^5 is tightened up on bolt D^2 not only will the rods be firmly gripped to prevent movement longitudinally of them but member D' will be firmly gripped between the arms of yoke D^3 to prevent swinging of said member D' . The result is that the roll D may be placed in the desired position longitudinally and angularly with relation to the rods G and G' and then fixed in that position. Pulley A^{10} is mounted in bearings g and g' connected by cross-piece g^2 , bearing g' being perforated to receive rod G' and to permit relative movement between it and said rod, and bearing g being similarly perforated to receive rod G . Rod G' has abutment g^2 for coiled spring g^3 which also abuts against bearing g' . Coiled spring g^4 is similarly provided for rod G . These springs act as a take-up for belt A^5 .

An important advantage of my machine is that the lower receiving member will yield under the influence of the blanks, partly on account of the weight of the blanks and partly on account of their wedging action between the upper and lower receiving members.

Another important advantage is that both the upper delivery mechanism and the upper receiving mechanism are adjustable to give a largely increased range for use with blanks of different sizes.

Another important advantage is that the position of delivery of the upper delivery belt is adjustable without substantial change of the length of the belt.

What I claim is:

1. Mechanism of the character described comprising delivery means; and receiving means including a slack belt yieldable at a portion of its travel under the influence of the blanks; and means tending to raise said belt at said portion of its travel.

2. Mechanism of the character described comprising delivery means; and receiving means including a slack belt yieldable at a portion of its travel under the influence of the blanks; a pivoted member having at one side of its pivot a part to engage said belt at said portion of its travel and weight-

ed at the other side of the pivot and tending to raise said engaging part.

3. Mechanism of the character described comprising delivery means; an upper receiving belt carried in part by a pulley having an axis which is fixed during operation of the mechanism; a slack lower receiving belt yieldable at a portion of its travel under the weight of the blanks; and a pivoted member having at one side of its pivot a roller to engage said belt at said portion and having at the other side of the pivot a counterweight tending to raise said roller, the latter when in its uppermost position having its axis substantially in line vertically with the fixed axis of said pulley and when in its lowermost position being in engagement with the lower face of the upper stretch, and with the upper face of the lower stretch, of said lower receiving belt.

4. Mechanism of the character described comprising a lower delivery belt; an upper delivery belt extending in advance of said lower belt at least the length of each blank being delivered; and means in advance of the lower belt and to the rear of the forward end of the upper belt tending to force downwardly the rear end of each blank as it leaves the lower delivery belt.

30 5. Mechanism of the character described comprising a lower delivery belt; an upper delivery belt; a pulley for the forward end of said belt, in advance of the lower belt; the bottom of said pulley being lower than the upper stretch of said lower belt; and a roller to engage the upper face of the lower stretch of the upper belt between the lower delivery belt and said pulley, the bottom of said roller being below the line from the bottom of said pulley to the upper stretch of the lower delivery pulley, the axis of said roller being fixed.

6. Mechanism of the character described comprising receiving means including upper and lower cooperating members, the lower member being yieldable downwardly under the influence of the blanks; means to drive positively one of said members; and means for delivering the blanks to the receiving means successively and in overlapped relation.

7. Mechanism of the character described comprising a lower receiving conveyor yieldable downwardly under the influence of the blanks; an upper receiving belt; means to drive positively said upper belt; and means for delivering the blanks successively and in overlapped relation to said conveyor and belt.

80 8. Mechanism of the character described

comprising delivery means; a lower receiving conveyor; an upper receiving belt; and means including a chain for driving positively said belt.

9. Mechanism of the character described comprising delivery means; a lower receiving conveyor; an upper belt; and means including a chain for driving positively said belt, said means being adjustable to conform with the position of said belt longitudinally of the mechanism.

10. Mechanism of the character described comprising receiving means; and delivery means including a belt which is adjustable longitudinally of the mechanism.

11. Mechanism of the character described comprising lower delivery means; lower receiving means; upper delivery means which is adjustable longitudinally of the mechanism; and upper receiving means which is adjustable longitudinally of the mechanism.

12. Mechanism of the character described comprising receiving means; lower delivery means; and upper delivery means which is adjustable longitudinally and angularly.

13. Mechanism of the character described comprising receiving means; and a delivery belt whose position of delivery is adjustable without substantial change of the length of said belt.

14. Mechanism of the character described comprising delivery means; and receiving means including a slack belt yieldable at a portion of its travel under the influence of the blanks; a pivoted member having at one side of its pivot a part to engage said belt at said portion of its travel; and means at the other side of said pivot tending to raise said engaging part.

15. Mechanism of the character described comprising a lower delivery belt; a forward pulley for said lower belt; an upper delivery belt extending in advance of said lower belt; a forward pulley for said upper belt; and means to force downwardly the rear end of each blank as it leaves the lower delivery belt, said means extending below the line which extends from the bottom of said pulley for the upper belt to the top of said pulley for the lower belt.

16. Mechanism of the character described comprising a lower delivery belt; an upper delivery belt extending in advance of said lower belt substantially the length of each blank being delivered; and means in advance of the lower belt and to the rear of the forward end of the upper belt tending to force downwardly the rear end of each blank as it leaves the lower delivery belt.

HAROLD S. LABOMBARDE.
